UNITED STATES PATENT OFFICE.

HERVY LINWOOD TRIMYER, OF PORTSMOUTH, VIRGINIA.

LADDER.

1,157,602.

Specification of Letters Patent.

Patented Oct. 19, 1915.

Application filed September 13, 1911. Serial No. 649,064.

To all whom it may concern:

Be it known that I, HERVY L. TRIMYER, a citizen of the United States, and a resident of Portsmouth, in the county of Norfolk and State of Virginia, have invented certain new and useful Improvements in Ladders, of which the following is a specification.

My present invention relates in general 10 to ladders, and more particularly to ladders used for scaling railway cars and has special reference to the construction of a combined scaling ladder, sill step, and roof grab-iron.

15 The principal objects of my present invention are the provision of an improved form of ladder construction wherein the sill step is carried by the ladder, and one wherein in the roof grab-iron may also be carried by 20 the ladder or by the means for attaching the ladder to the car; the provision of improved means for attaching the ladder to the car whereby the ladder may be held in position in a much more simple and eco- 25 nomical manner than is at present known to me, and whereby the ladder may be so attached in the manner required under approved modern practice without making it necessary to disturb the lining or any other 30 part of the inside of the car; the provision of an improved form of construction wherein, in the event of accident, the parts most liable to injury may readily be renewed without disturbance of the remaining parts 35 at the time of such replacement; the provision of a greatly simplified and improved form of car ladder construction wherein not only are the number of parts required in its manufacture greatly reduced, thus cheap- 40 ening the cost of manufacture, but also the number of parts required for attaching it in position greatly reduced, thus lessening the danger of personal injury to the user, together with such further objects as may 45 be below disclosed.

In the ladder constructions commonly employed at this day, wooden cars generally have a sill step bolted to the side with four bolts, or in the case of a steel car two rivets 50 or bolts. If one of the bolts or rivets breaks, or a head or nut is lost, the user is almost invariably injured. Again, in the ordinary construction, six ladder treads, held in place by twelve bolts or clamp screws are com- 55 monly used, and the failure of one of them

or the loss of a nut or screw, likewise almost invariably results in injury to the user. Furthermore the roof grab-iron is generally one of the most insecure and one of the most fruitful sources of injury, of all railway car 60 attachments, since it is customarily bolted or screwed through the roof at a point where it is difficult to obtain and maintain screw fastenings, and owing to the inaccessibility of its location, in practice, ordinary 65 does not secure the required inspection received by other parts of the car.

Modern approved practice requires a larger number of ladder treads than have heretofore been used, thus largely increasing 70 the number of points to be fastened, and since such approved practice further requires the use of bolts or rivets in all ladder, iron, and step construction, much difficulty is found in properly placing the attaching 75 members in the ends of the ladder treads next to the corner of the car, owing to the interference of the corner bands and corner posts and other members commonly employed in modern car construction, owing 80 to the obstructions presented thereby, as well as for other reasons, further difficulty is experienced in securing from car-builders and repairers proper relative location of the scaling ladder, sill step and roof grab-iron. 85

In gaining the objects above stated, as well as certain further benefits and advantages to be below pointed out, and in overcoming the disadvantages and objections referred to, I have provided a construction, 90 of which one embodiment wherein the roof grab-irons and sill steps are permanently located by attachment to the scaling ladder proper, is illustrated in the accompanying drawings, where-in—

Figure 1 is an elevational view illustrative of an application of my improved form of construction to the side of a box car, near the end thereof; Fig. 2 is an elevational view of a portion of the end of the car of Fig. 1, taken at right angles to the position shown in such figure; Fig. 3 is a plan view of a portion of the roof of the car of Figs. 1 and 2; Fig. 4 is a view showing a modified form of the sill step construction; Fig. 5 is a view of a detail of construction; Fig. 6 is an enlarged fragmentary view of a modified detail of construction; Fig. 7 is a sectional view taken on the line VII—VII of Fig. 6; Fig. 8 is an enlarged fragmentary 110

view, partly in section illustrative of a detail of construction; and Fig. 9 is a view of a modified detail.

Referring now more particularly to Figs. 5, 1, 2 and 3, it will be observed that in carrying out my invention I employ, for the construction of the side ladder, a member 10, preferably a flat continuous steel strap as illustrated in Fig. 1, bent at 11 and 12 to 10 provide a step 13 and parallel stiles 14 and 15, such stiles 14 and 15 being apertured at 16-16, 17-17, to receive the tread members 18-18. In order that each of the treads may act as spacing members, and also in 15 order to facilitate their implacement, they are preferably provided at each end with a shoulder as indicated at 19 (see Fig. 8) so that when the rivet heads 20' are formed, any relative movement between the treads 18 and the stiles 14 and 15 will be prevented. 20 At the upper end of the ladder, thus formed, I attach to the ends 20, 21 of the stiles conveniently by means of bolts indicated at 22, 23, a roof grab iron 24, which is preferably 25 the forging illustrated in Fig. 3, described more particularly below.

For the purpose of holding the upper part of the ladder firmly in contact with the roof of the car, to the end that it may 30 be supported therefrom, the stiles 14 and 15 are preferably given a quarter turn as indicated at 26, 27, before bending at 26'-27', so that the flat side of the strap may contact with such roof and the support of 35 the structure thereby aided.

For spacing the ladder away from the side of the car in order to facilitate its use, and for permanently holding it in fixed position, I employ suitable attaching means, 40 here shown as angle irons 28-28 and 29-29, such angle irons being preferably riveted to the stiles 14 and 15 and bolted through the car siding.

In order most securely to brace the ladder 45 against thrusts, the angles 28 to 29 are preferably located exteriorally of the stiles 14 and 15, but where the construction of the car so demands, the angles 29 may be located between the stiles 14 and 15 as indicated 50 in dotted lines in Fig. 1, without sacrifice of the desirable spacing between the ladder and the end of the car. To the end that the step 13 may be saved, as far as may be, from injury by striking obstructions adjacent 55 the track, and on the other hand to prevent accidents ensuing upon a projecting step striking careless bystanders, the stiles 14 and 15 are preferably off-set as indicated at 30, 31 in order to bring the step 13 adjacent or within the vertical line of the car body indicated at 32.

On viewing more particularly Fig. 2, wherein I have illustrated my improvements applied to an end ladder, it will be 60 apparent that the members 10', 14', 15', 18',

28' 29' are in all substantial respects the same as the corresponding members in Fig. 1, save that no step is here ordinarily used and that the vertical stile 14' is not necessarily, though it may conveniently be, continued over the roof of the car, and that the vertical stile 15' as well as receiving the quarter turn indicated at 27'' and bend 27' is materially bent laterally, as indicated at, 75 33 in order to increase the available length of the grab iron 24', such grab iron being preferably a continuation of the grab iron 24, attached to the said lateral extension 33 by a bolt 34.

Referring now more particularly to Fig. 4, it will be seen that in the form of construction here illustrated, the stiles 14' and 15', at their lower ends, (instead of being formed of a continuous strap, as shown in Figs. 1 and 2), in order to provide the sill 80 step, has a step 13' made of a separate strap, preferably bolted to such stiles as indicated at 34, 35, the advantage of such construction being that in the event that distortion or breakage of the step 13' through accident 85 require repair or removal thereof, there be no necessity of dismounting the entire ladder, but that the step alone may be removed for repair, or a new one implaced, by a mere removal of the bolts 34, 35, and without disturbance of the remainder of the apparatus. If it be desired to gain additional spacing 90 between the lowest of the rungs 18' and the car-body, a separate rung 18'' may be inserted between the separated stile members 95 14'' and 15'' as shown in Fig. 9. Considering now more particularly the grab iron construction 24-24', it will be noted that for spacing it away from the roof so that it 100 may be readily grasped and for attaching it in position, this member may be conveniently made of a rod given a substantially right angled bend 36, and having its ends provided with downwardly and laterally disposed portions 38, 39, terminating in 110 eyes 40, 41, a third extension 37 terminating in an eye 42 being welded thereto, (Fig. 5), or, if desired, in order to avoid the expense of forging or welding the intermediate member 37 in position, a separate member 115 37' having at one end the eye 42' and at the opposite end an eye 43 engaging the member 24 may be employed.

From the foregoing description and examination of Figs. 1 and 2 of the drawings, 120 it will be observed that the combined scaling ladder, sill step and grab iron is supported directly by the roof, and the weight thereof and of the user is borne primarily by the roof and thence distributed through 125 its supports, and that the fastening devices and siding, instead of carrying directly the entire weight of the ladder or any material portion thereof, or of the user, serve primarily to hold the ladder and parts carried 130

thereby fixedly in position, and merely secondarily to support the same; that hence, in the event of breakage or loss of one or more of the attaching members such as are indicated at 28, 29, an accident does not necessarily follow; and that one of such attaching devices remaining intact and holding the ladder in position, will still serve to sustain the ladder and any user thereof. Furthermore that in the event of injury to any part of the ladder, such part, by employing my invention, may be readily repaired or renewed; that all of the several parts including the sill step, ladder rung and grab irons, are at all times properly spaced and maintained in proper fixed relation to one another and to the car; and that by virtue of the disposition of the step 13 injury either to users or bystanders is rendered much less likely. Other advantages of the construction are that the disposition of the members 28—29 on the stiles may be varied vertically as well as laterally in order to avoid any obstruction to the fastening thereof in position, and that by virtue of the vertical stile construction as distinguished from the customary isolated tread construction, sliding off of the user's feet with consequent likelihood of his falling, especially when stepping around the corner of the car above the sill step, is largely prevented.

Having thus described my invention and illustrated its use, what I claim as new and desire to secure by Letters Patent is:

1. The combination with a car, of an end ladder and a side ladder, the stiles of said side ladder being bent over the roof of the car, a member connected to the end of one stile extending beyond the end of the other stile, and one of the stiles of said end ladder being bent over the roof of the car and being secured to said member, said member serving as a roof grab for the end ladder.

2. The combination with a car, of an end ladder and a side ladder, one of the stiles of said side ladder being bent over the roof of the car, a member connected to said stile extending beyond the end of the other of said stiles, and one of the stiles of said end ladder being bent over the roof of the car and being secured to said member.

3. The combination with a car, of an end ladder and a side ladder, one of the stiles of said side ladder being bent over the roof of the car, a member connected to said stile extending beyond the end of the other of said stiles, and one of the stiles of said end ladder being bent over the roof of the car and being secured to said extension, said member serving as a roof grab for the end ladder.

4. The combination with a car, of an end ladder and a side ladder, the stiles of said side ladder being bent over the roof of the car, a member connected to one of said stiles extending beyond the end of the other of

said stiles, and one of the stiles of said end ladder being bent over the roof of the car and being secured to said member, said member serving as a roof grab for the end ladder.

5. The combination with a car, of an end ladder and a side ladder, one of the stiles of said side ladder being bent over the roof of the car, a member connected to the end of said stile extending beyond the end of the other of said stiles, and one of the stiles of said end ladder being bent over the roof of the car and being secured to said extension, said member serving as a roof grab for the end ladder, and a rung fixed to the bent over portion of the side ladder and serving as a roof grab for the side ladder.

6. The combination with a car, of an end ladder and a side ladder, one of the stiles of said side ladder being bent over the roof of the car, a member connected to said stile extending beyond the end of the other of said stiles, and one of the stiles of said end ladder being bent over the roof of the car and being secured to said member, said member serving as a roof grab for the end ladder, and a rung formed integrally with said member disposed adjacent the bent over portion of the side ladder and serving as a roof grab for the side ladder.

7. The combination with a car, of an end ladder and a side ladder, one of the stiles of said side ladder being bent over the roof of the car, a member connected to said stile extending beyond the end of the other of said stiles, and one of the stiles of said end ladder being bent over the roof of the car and being secured to said member, said member serving as a roof grab for the end ladder, a rung fixed to the bent over portion of the side ladder and serving as a roof grab for the side ladder, said ladders being respectively secured at their bottoms to the side and end of the car, and means carried by the car body for spacing said ladders from the car body, said spacing means constituting an auxiliary fastening means.

8. The combination with a car, of an end ladder and a side ladder, one of the stiles of said side ladder being bent over the roof of the car, a member connected to the end of one stile extending beyond the end of the other of said stiles, and one of the stiles of said end ladder being bent over the roof of the car and being secured to said member, said member serving as a roof grab for the end ladder, a rung fixed to the bent over portions of the side ladder and serving as a roof grab for the side ladder, said ladders being respectively secured at their bottoms to the side and end of the car.

9. The combination with a car, of an end ladder and a side ladder, one of the stiles of said side ladder being bent over the roof of the car a member connected to said stile

- extending beyond the end of the other of said stiles, and one of the stiles of said end ladder being bent over the roof of the car and being secured to said member, said member serving as a roof grab for the end ladder, a rung formed integrally with said member disposed adjacent the bent over portions of the side ladder and serving as a roof grab for the side ladder, said ladders being respectively secured at their bottoms to the side and end of the car.
10. The combination with a car, of an end ladder and a side ladder, the stiles of said ladder being bent over the roof of the car, a member connected to one of said stiles and extending beyond the end of the other of said stiles, and one of the stiles of said end ladder being bent over the roof of the car and being secured to said member, said member serving as a roof grab for the end ladder, and a rung disposed between the bent over portions of the side ladder and serving as a roof grab for the side ladder.
15. The combination with a car, of an end ladder and a side ladder, the stiles of said side ladder being bent over the roof of the car, a member connected to one of said stiles extending beyond the end of the other of said stiles, and one of the stiles of said end ladder being bent over the roof of the car and being secured to said member, said member serving as a roof grab for the end ladder, a rung disposed between the bent over portions of the side ladder and serving as a roof grab for the side ladder, each of said ladders being secured at their bottoms to the sill of the car, and means carried by the car body for spacing said ladders from the car body, said spacing means constituting an auxiliary fastening means.
20. In combination with a car body having a roof, a plurality of car ladders located adjacent the corner of the car, one at the side and one at the end of the car, and a common roof grab iron for said ladders carried by said ladders.
25. In combination with a car body having a roof, a plurality of car ladders located adjacent the corner of the car, one at the side and one at the end of the car, and a common grab-iron for said ladders carried by said ladders, one of said ladders being connected by their stiles to the roof of the car.
30. In combination with a car body having a roof, a plurality of car ladders located adjacent the corner of the car, one at the side and one at the end of the car, and a common grab-iron fixing said ladders together, said grab iron being connected directly to said ladders.
35. In combination with a car body having a roof, a plurality of car ladders located adjacent the corner of the car, one at the side and one at the end of the car, the said ladders having a common structural element connected thereto, whereby they are united and a portion of their weight is carried by the roof of the car.
40. In combination with a car body having a roof, a plurality of car ladders located adjacent the corner of the car, one at the side and one at the end of the car, the said ladders having a common structural element connected thereto, whereby they are united and a portion of their weight is carried by the roof of the car.
45. In combination with a car body having a roof, a plurality of car ladders located adjacent the corner of the car, one at the side and one at the end of the car, and a common grab-iron for said ladders carried by said ladders, one of said ladders being connected by their stiles to the roof of the car.
50. In combination with a car body having a roof, a plurality of car ladders located adjacent the corner of the car, one at the side and one at the end of the car, and a common grab-iron fixing said ladders together, said grab iron being connected directly to said ladders.
55. In combination with a car body having a roof, a plurality of car ladders located adjacent the corner of the car, one at the side and one at the end of the car, the said ladders having a common structural element connected thereto, whereby they are united and a portion of their weight is carried by the roof of the car.
60. In combination with a car body having a roof, a plurality of car ladders located adjacent the corner of the car, one at the side and one at the end of the car, and a common grab-iron for said ladders carried by said ladders, one of said ladders being connected by their stiles to the roof of the car.
65. In combination with a car body having a roof, a plurality of car ladders located adjacent the corner of the car, one at the side and one at the end of the car, the said ladders having a common structural element connected thereto, whereby they are united and a portion of their weight is carried by the roof of the car.
70. In testimony whereof I have hereunto signed my name in the presence of the two subscribed witnesses.
